UNITED STATES PATENT OFFICE

159,393

RECEPTACLE OR SIMILAR ARTICLE

Pearl Roche, Meadville, Pa.

Application April 5, 1949, Serial No. 1,819

Term of patent 14 years

(Cl. D58—11)

To all whom it may concern:

Be it known that I, Pearl Roche, a citizen of the United States of America, residing at Meadville, county of Crawford, and State of Pennsylvania, have invented a new, original, and ornamental Design for a Receptacle or Similar Article, of which the following is a specification, reference being had to the accompanying drawing, forming a part thereof, wherein:

Figure 1 is a perspective view of the receptacle or similar article, showing my new design;

I claim:

The ornamental design for a receptacle or similar article, as shown.

PEARL ROCHE.
